(57) CLAIM

An ornamental design for a cooking grill, as shown and described.

DESCRIPTION

FIG. 1 is a top rear right perspective view of a cooking grill showing our new design;

FIG. 2 is a top rear left perspective view thereof;

FIG. 3 is a top front left perspective view thereof;

FIG. 4 is a top front right perspective view thereof;

FIG. 5 is a bottom rear right perspective view thereof;

FIG. 6 is a bottom rear left perspective view thereof;

FIG. 7 is a bottom front left perspective view thereof;

FIG. 8 is a bottom front right perspective view thereof;

FIG. 9 is a top front right perspective view of the cooking grill in an open position;

FIG. 10 is a top front left perspective view thereof;

FIG. 11 is a front view thereof;

FIG. 12 is a rear view thereof;

FIG. 13 is a left side view thereof;

FIG. 14 is a right side view thereof;

FIG. 15 is a top plan view thereof; and,

FIG. 16 is a bottom plan view thereof.
